UNITED STATES PATENT OFFICE.

GLENN J. BARRETT, OF GRAND RAPIDS, MICHIGAN, ASSIGNOR, BY MESNE ASSIGNMENTS, TO BARRETT ADDING MACHINE CO., OF GRAND RAPIDS, MICHIGAN, A CORPORATION.

KEY-SET CALCULATING-MACHINE.

1,003,086.

Specification of Letters Patent. Patented Sept. 12, 1911.

Application filed June 7, 1910. Serial No. 585,562.

To all whom it may concern:

Be it known that I, GLENN J. BARRETT, a citizen of the United States, residing at Grand Rapids, Kent county, Michigan, have 5 invented certain new and useful Improvements in Key-Set Calculating-Machines, of which the following is a specification.

This invention relates to improvements in key-set calculating machines.

10 The main objects of the invention are: First, to provide means of readily determining the complement of a number in the process of subtraction without the necessity of placing two numerals upon the finger key 15 itself. Second, to provide a convenient means of splitting the machine at any desired point; in other words, to arrest the carrying operation at any convenient denomination and thus provide means for automatically 20 counting the handle strokes.

Further objects, and objects relating to structural details, will definitely appear from the detailed description to follow.

I accomplish the objects of my invention 25 by the devices and means described in the following specification.

The structure described constitutes one effective embodiment of my invention.

Other embodiments would be readily de- 30 vised by those skilled in the art.

The invention is clearly defined and pointed out in the claims.

A structure constituting an effective and preferred embodiment of the features of my 35 invention is clearly illustrated in the accompanying drawing, forming a part of this specification, in which:

Figure 1 is a plan view of an adding machine to which my invention is applied. 40 Fig. 2 is a detail sectional view taken on the irregular line 2—2 of Fig. 1 of the top plate of the machine showing a portion of the two key stems and the counting switch. Fig. 3 is a detail plan view of one of the counting 45 switches with one of the co-operating key systems in section. Fig. 4 is a detail sectional side elevation of an adding machine taken on line 4—4 of Fig. 1. Fig. 5 is a detail sectional view of the splitting push 50 bar on line 5—5 of Fig. 4. Fig. 6 is a detail sectional view of one of the dial actuating members on line 6—6 of Fig. 4, showing par-

ticularly the pin 15 and its relation to the splitting push bar 12. Fig. 7 is a side elevation of the push bar 11. Fig. 8 is an enlarged 55 detail perspective view of a key stem release slide and dial actuator. Fig. 9 is an enlarged detail fragmentary view of the register or accumulating mechanism, showing the transfer mechanism and its relation to 60 the dials and other parts. Fig. 10 is an enlarged detail sectional elevation of the number wheels in connection with the transfer mechanism or accumulating mechanism, taken on a line corresponding to line 10—10 65 of Fig. 9. Fig. 11 is a detail sectional view taken on a line corresponding to line 11—11 of Fig. 10, showing details of the transfer mechanism. Fig. 12 is an enlarged detail elevation view taken on a line corresponding 70 to line 12—12 of Figs. 9 and 13. Fig. 13 is an enlarged detail sectional view partially in full line taken on a line corresponding to line 13—13 of Fig. 12. Fig. 14 is an enlarged detail view taken on a line corre- 75 sponding to line 14—14 of Fig. 13. Fig. 15 is an enlarged detail elevation view taken on a line corresponding to line 15—15 of Fig. 13, showing details of the carrying cam means with actuating connections therefor. 80

In the drawings, similar reference characters refer to similar parts throughout the several views, and the sectional views are taken looking in the direction of the little arrows at the ends of the section lines. 85

My invention is shown applied to a calculating machine having a full key-board as shown in Fig. 1. The details of construction of the general accumulating features are im- 90 material to my invention.

The machine I have shown herewith to which my invention is applied is of the handle driven type, and has a set of accumulating dials 25 at the front. The keys 7 of the key board are depressible and latch in de- 95 pressed positions.

In the machine shown herewith the key stem 8 is latched by the engagement of the notch 22 under the plate 20, and in so doing, by reason of the beveled portion 21, when the 100 key is depressed, the lower extremity of the key stem is forced rearwardly and this rearward movement moves the slide 17 which in turn lifts the latch 23, as hereinafter de-

scribed. The key stems are unlatched during the operation of the machine by forcing rearwardly the slide 17, but the various forms of these mechanisms are immaterial to my invention and need no further description.

In this machine, an operating handle 4 is provided which accumulates the amounts indicated by the depressed keys in the usual way. By operation of the handle 4, the 10 number shown upon the depressed key is accumulated into the dial section corresponding to the denomination or row in which said key was depressed. During the return stroke of said operating handle, the 15 key stem is released and returns to normal position. In the machine which I have shown, the dial actuating mechanism appears as the reciprocating member 13 and its connection. The depression of any key 20 stem interposes a stop in the path of travel of this reciprocating member 13. During the forward movement of the handle 4 this reciprocating member 13 goes forward until arrested by said key stem. The return movement 25 of said handle restores the member 13 to normal position during which latter operation the amount represented by the key stem is accumulated into the coöperating dial. Normally, when no finger key is 30 depressed, the checking latch 23 restrains its coöperating reciprocating member so that during the movement of the handle the reciprocating member does not go forward. However, when the key stem is depressed 35 in any column, this latch 23 is elevated out of the path of travel of the restraining pin 23' and then the member 13 is free to go forward during the operation of the handle.

In the machine I have shown, the lower 40 end of the key stem itself is the stop which arrests the member 13 in its forward movement. Reciprocating members arrested by suitable stops actuated by key stems which in turn release such reciprocating members 45 and handle operating mechanism for accumulating, with proper dial coöperating mechanism, are common to machines of the class described. My invention does not relate to these details.

50 The shaft 19, (see Fig. 4) is attached to the handle 4, and from this shaft coöperating control mechanism swings the pick-up bail 14 forwardly, the movement of which allows the reciprocating member 13 to go 55 forward.

It is very desirable in machines of this class to provide some means of counting the handle strokes automatically. In my invention shown herewith, I have accomplished 60 this object in a simple and convenient manner. I have planned to utilize dials at the left of the series for this purpose, arranging devices to add "1" in a certain dial every time the handle is operated. There 65 being regular carrying mechanism for carry-

ing over the tens, this process will keep accurate count of the handle movements.

In the machine I have shown, it will be assumed that there is a means for resetting the dials to the "0" point, as is common in 70 machines of this class. When the dials to the right of the series are returned to the "0" point, the counter also resets itself, thereby clearing itself for a new series. The means for accomplishing this purpose will 75 be understood by reference to the drawings, and particularly to Fig. 4. I have provided devices for throwing out the latch 23 in the desired column, which as explained, will allow the reciprocating slide 17 to go forward and 80 then at the same time interpose a stop in the path of travel of this reciprocating member, whatever may be its form, which will allow the member to go forward one space which adds "1" in its coöperating dial at 85 every handle movement. It will be readily seen that if the key stem, in the "1" row be depressed and locked down, that this condition is met,—namely, that the latch is elevated out of engaging relation with its coöperating reciprocating member and at the same time the stop is interposed, allowing 90 said reciprocating member to advance forwardly one space at every handle movement. This can be understood, noting that the end 95 of the key stem 8^a is offset and will arrest the member 13 by contact with the projecting lug 13^a thereon. The exact form of accomplishing this result is not material to my invention and will admit of many variations. 100 I have shown herewith two methods of accomplishing this result which are provided for the convenience of the operator, either to be used at his option. Aside from depressing and locking down a desired finger 105 key the latch 23 may be rendered inoperative and a suitable independent stop interposed by the depression of a push bar 11 shown in Fig. 7. This bar has formed upon it the cam surface 11^a which passes through 110 an opening 17' in the slide 17. This slide 17 is adapted to be actuated rearwardly by the depression of any finger key in its coöperating column and is connected to the latch 23 for the purpose described. The 115 push bar 11 is guided in the plate 18 which extends across the machine. Thus it will be seen that the cam surface 11^a coöperating against slide 17 will force the latter rearwardly upon depression and this will elevate the latch 23, disengaging the same from the pin 23'.

Upon the coöperating reciprocating member 13 is the pin 16. When the push bar 11 is depressed, it comes in the path of travel 125 of this pin and arrests the forward movement of said member 13 at a point which will cause the accumulation of "1" in the dial of this denomination when the handle returns to normal position. In other words, 130

this push bar in this regard performs the same function as a finger key and simply amounts to another special finger key for this special purpose. In this connection, it 5 may be stated that the push bars 11 in the illustration shown are provided opposite the last six dials. Ordinarily it may be desirable to place them only opposite the last two or three dials, but the number is immaterial to my invention. The push bars 11 are provided with a notch 11' to engage the top of case "1". In general, it will be understood that when one of the push bars 11 is depressed and the notch 11' locked under 10 the case "1" of the machine, that the dial opposite will continue to rotate one space at every handle movement, and that the tens will be carried over into the next dial to the left. Upon release of this push bar, 15 and during the regular resetting operation common to machines of this class, these counting dials will be reset at the same time as the others.

If it is desired to lock down the key stem 20 instead of push the push bar 11, I have provided the counting switch 5 pivotally mounted on the top plate 2 of the machine. This switch has engaging portions 10 and 10' which coöperate with notches 8' in the operating key stems. Fig. 3 shows how this switch engages said notch and locks the key stem down so that the regular releasing mechanism operated during the handle stroke, has no effect upon this key and it 25 remains down and the dial opposite said key continues to add "1" thereon at every handle operation. These switches are arranged to engage either of two key stems, being moved either to the right or to the 30 left.

In conjunction with the push bar system of providing counting mechanism, I have provided a means of splitting the machine, or means of stopping the carrying operation beyond a desired denomination. In 35 other words, when one of these push bars 11 is depressed, it automatically prevents the carrying over of the tens from the dial to the right which would render the count 40 inaccurate. Fig. 7 shows the form of this push bar 11, and there may be as many of them in the machine as desired. Upon the member 13 will be noted the pin 15. When 45 11 is depressed and locked down, it falls behind this pin 15 and prevents any further backward movement of the member 13 which it will be understood normally moves one space backwardly when the dial of next 50 lower denomination passes the transfer point.

55 Mechanism for accomplishing this carrying operation is immaterial to my invention and is not described, as this additional rearward movement of one space for carrying is a common feature in machines of this class.

60 65 A structure showing these features is fully

illustrated in my Patent No. 976,336 of November 22, 1910, certain figures of which have been reproduced and a description of the same appended. The carrying is accomplished by reason of intermediate connections to the reciprocating members or digit slides 13. A carrying stop 115 for each dial is pivotally mounted upon the shaft 117, coöperating with each dial sector 107. A spring 406 holds same in normal 70 position. This stop 115 has an ear 115' offset and extending toward the left of the machine (see Fig. 11), which is adapted to arrest the movement of the digit stop arm 121. A finger 115" extends toward the 75 right of the machine from arm 115, and carries the tripping pin 119 which normally lies in the path of travel of the carrying cams 106. As the push bars 208 from their connections force the racks 205 and the sectors 107 rearwardly when they have reached the desired point, the digit stop arm 121 contacts with the ear 115' and arrests the swinging movement of said sector 107 and rack 205. 80 A continued movement of the push bar 208 causes the spring 501 to open and push bar moves on slide 213 a distance equal to a one space movement of the dial. It will be readily seen that if the stop ear 115' be moved toward the rear of the machine and 85 out of stopping contact with the digit stop arm 121, the sector will then swing an additional space farther than that which would be ordinarily imparted by reason of the regular movement of the digit slide. 90 The carrying cams 106 are located near the left end of the dial space, and coöperate with the tripping pins 119, of the dial space of next higher denomination, back, allowing the digit stop arm 121 of the next higher 95 100 denomination to swing an additional space, thus carrying ten from a lower denomination to a higher. If a carrying cam 106 passes the carrying point while the stopping arms are away from the stops 115', for 105 instance, in adding "8" and "8", then the carrying catch 118 supported on the shaft 8 engages the ear 115' at the rearward limit of the movement imparted to it by the carrying cam 106, and holds this ear 115' out 110 of the path of travel of the digit stop arm 121 of the next higher denomination, until this arm swings around driven by its respective rack, thereby causing the dial of next higher denomination to move an extra space because of the withdrawal of the 115 stop 115'. When this stop arm 121 moves this additional space, the catch 118 is automatically disengaged from the ear 115' and the next time the handle is drawn forward, 120 the carrying parts rest themselves or move into position for another carrying operation. An important feature of my invention in this connection is that the carrying movement is not stored in any portion of the 125 130

digit sliding member proper. In other words, there is a perfectly rigid connection between the stopping ears on the digit slide and the dials themselves, for if there were a 5 ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ⁴¹¹⁵ ⁴¹²⁰ ⁴¹²⁵ ⁴¹³⁰ ⁴¹³⁵ ⁴¹⁴⁰ ⁴¹⁴⁵ ⁴¹⁵⁰ ⁴¹⁵⁵ ⁴¹⁶⁰ ⁴¹⁶⁵ ⁴¹⁷⁰ ⁴¹⁷⁵ ⁴¹⁸⁰ ⁴¹⁸⁵ ⁴¹⁹⁰ ⁴¹⁹⁵ ⁴²⁰⁰ ⁴²⁰⁵ ⁴²¹⁰ ⁴²¹⁵ ⁴²²⁰ ⁴²²⁵ ⁴²³⁰ ⁴²³⁵ ⁴²⁴⁰ ⁴²⁴⁵ ⁴²⁵⁰ ⁴²⁵⁵ ⁴²⁶⁰ ⁴²⁶⁵ ⁴²⁷⁰ ⁴²⁷⁵ ⁴²⁸⁰ ⁴²⁸⁵ ⁴²⁹⁰ ⁴²⁹⁵ ⁴³⁰⁰ ⁴³⁰⁵ ⁴³¹⁰ ⁴³¹⁵ ⁴³²⁰ ⁴³²⁵ ⁴³³⁰ ⁴³³⁵ ⁴³⁴⁰ ⁴³⁴⁵ ⁴³⁵⁰ ⁴³⁵⁵ ⁴³⁶⁰ ⁴³⁶⁵ ⁴³⁷⁰ ⁴³⁷⁵ ⁴³⁸⁰ ⁴³⁸⁵ ⁴³⁹⁰ ⁴³⁹⁵ ⁴⁴⁰⁰ ⁴⁴⁰⁵ ⁴⁴¹⁰ ⁴⁴¹⁵ ⁴⁴²⁰ ⁴⁴²⁵ ⁴⁴³⁰ ⁴⁴³⁵ ⁴⁴⁴⁰ ⁴⁴⁴⁵ ⁴⁴⁵⁰ ⁴⁴⁵⁵ ⁴⁴⁶⁰ ⁴⁴⁶⁵ ⁴⁴⁷⁰ ⁴⁴⁷⁵ ⁴⁴⁸⁰ ⁴⁴⁸⁵ ⁴⁴⁹⁰ ⁴⁴⁹⁵ ⁴⁵⁰⁰ ⁴⁵⁰⁵ ⁴⁵¹⁰ ⁴⁵¹⁵ ⁴⁵²⁰ ⁴⁵²⁵ ⁴⁵³⁰ ⁴⁵³⁵ ⁴⁵⁴⁰ ⁴⁵⁴⁵ ⁴⁵⁵⁰ ⁴⁵⁵⁵ ⁴⁵⁶⁰ ⁴⁵⁶⁵ ⁴⁵⁷⁰ ⁴⁵⁷⁵ ⁴⁵⁸⁰ ⁴⁵⁸⁵ ⁴⁵⁹⁰ ⁴⁵⁹⁵ ⁴⁶⁰⁰ ⁴⁶⁰⁵ ⁴⁶¹⁰ ⁴⁶¹⁵ ⁴⁶²⁰ ⁴⁶²⁵ ⁴⁶³⁰ ⁴⁶³⁵ ⁴⁶⁴⁰ ⁴⁶⁴⁵ ⁴⁶⁵⁰ ⁴⁶⁵⁵ ⁴⁶⁶⁰ ⁴⁶⁶⁵ ⁴⁶⁷⁰ ⁴⁶⁷⁵ ⁴⁶⁸⁰ ⁴⁶⁸⁵ ⁴⁶⁹⁰ ⁴⁶⁹⁵ ⁴⁷⁰⁰ ⁴⁷⁰⁵ ⁴⁷¹⁰ ⁴⁷¹⁵ ⁴⁷²⁰ ⁴⁷²⁵ ⁴⁷³⁰ ⁴⁷³⁵ ⁴⁷⁴⁰ ⁴⁷⁴⁵ ⁴⁷⁵⁰ ⁴⁷⁵⁵ ⁴⁷⁶⁰ ⁴⁷⁶⁵ ⁴⁷⁷⁰ ⁴⁷⁷⁵ ⁴⁷⁸⁰ ⁴⁷⁸⁵ ⁴⁷⁹⁰ ⁴⁷⁹⁵ ⁴⁸⁰⁰ ⁴⁸⁰⁵ ⁴⁸¹⁰ ⁴⁸¹⁵ ⁴⁸²⁰ ⁴⁸²⁵ ⁴⁸³⁰ ⁴⁸³⁵ ⁴⁸⁴⁰ ⁴⁸⁴⁵ ⁴⁸⁵⁰ ⁴⁸⁵⁵ ⁴⁸⁶⁰ ⁴⁸⁶⁵ ⁴⁸⁷⁰ ⁴⁸⁷⁵ ⁴⁸⁸⁰ ⁴⁸⁸⁵ ⁴⁸⁹⁰ ⁴⁸⁹⁵ ⁴⁹⁰⁰ ⁴⁹⁰⁵ ⁴⁹¹⁰ ⁴⁹¹⁵ ⁴⁹²⁰ ⁴⁹²⁵ ⁴⁹³⁰ ⁴⁹³⁵ ⁴⁹⁴⁰ ⁴⁹⁴⁵ ⁴⁹⁵⁰ ⁴⁹⁵⁵ ⁴⁹⁶⁰ ⁴⁹⁶⁵ ⁴⁹⁷⁰ ⁴⁹⁷⁵ ⁴⁹⁸⁰ ⁴⁹⁸⁵ ⁴⁹⁹⁰ ⁴⁹⁹⁵ ⁵⁰⁰⁰ ⁵⁰⁰⁵ ⁵⁰¹⁰ ⁵⁰¹⁵ ⁵⁰²⁰ ⁵⁰²⁵ ⁵⁰³⁰ ⁵⁰³⁵ ⁵⁰⁴⁰ ⁵⁰⁴⁵ ⁵⁰⁵⁰ ⁵⁰⁵⁵ ⁵⁰⁶⁰ ⁵⁰⁶⁵ ⁵⁰⁷⁰ ⁵⁰⁷⁵ ⁵⁰⁸⁰ ⁵⁰⁸⁵ ⁵⁰⁹⁰ ⁵⁰⁹⁵ ⁵¹⁰⁰ ⁵¹⁰⁵ ⁵¹¹⁰ ⁵¹¹⁵ ⁵¹²⁰ ⁵¹²⁵ ⁵¹³⁰ ⁵¹³⁵ ⁵¹⁴⁰ ⁵¹⁴⁵ ⁵¹⁵⁰ ⁵¹⁵⁵ ⁵¹⁶⁰ ⁵¹⁶⁵ ⁵¹⁷⁰ ⁵¹⁷⁵ ⁵¹⁸⁰ ⁵¹⁸⁵ ⁵¹⁹⁰ ⁵¹⁹⁵ ⁵²⁰⁰ ⁵²⁰⁵ ⁵²¹⁰ ⁵²¹⁵ ⁵²²⁰ ⁵²²⁵ ⁵²³⁰ ⁵²³⁵ ⁵²⁴⁰ ⁵²⁴⁵ ⁵²⁵⁰ ⁵²⁵⁵ ⁵²⁶⁰ ⁵²⁶⁵ ⁵²⁷⁰ ⁵²⁷⁵ ⁵²⁸⁰ ⁵²⁸⁵ ⁵²⁹⁰ ⁵²⁹⁵ ⁵³⁰⁰ ⁵³⁰⁵ ⁵³¹⁰ ⁵³¹⁵ ⁵³²⁰ ⁵³²⁵ ⁵³³⁰ ⁵³³⁵ ⁵³⁴⁰ ⁵³⁴⁵ ⁵³⁵⁰ ⁵³⁵⁵ ⁵³⁶⁰ ⁵³⁶⁵ ⁵³⁷⁰ ⁵³⁷⁵ ⁵³⁸⁰ ⁵³⁸⁵ ⁵³⁹⁰ ⁵³⁹⁵ ⁵⁴⁰⁰ ⁵⁴⁰⁵ ⁵⁴¹⁰ ⁵⁴¹⁵ ⁵⁴²⁰ ⁵⁴²⁵ ⁵⁴³⁰ ⁵⁴³⁵ ⁵⁴⁴⁰ ⁵⁴⁴⁵ ⁵⁴⁵⁰ ⁵⁴⁵⁵ ⁵⁴⁶⁰ ⁵⁴⁶⁵ ⁵⁴⁷⁰ ⁵⁴⁷⁵ ⁵⁴⁸⁰ ⁵⁴⁸⁵ ⁵⁴⁹⁰ ⁵⁴⁹⁵ ⁵⁵⁰⁰ ⁵⁵⁰⁵ ⁵⁵¹⁰ ⁵⁵¹⁵ ⁵⁵²⁰ ⁵⁵²⁵ ⁵⁵³⁰ ⁵⁵³⁵ ⁵⁵⁴⁰ ⁵⁵⁴⁵ ⁵⁵⁵⁰ ⁵⁵⁵⁵ ⁵⁵⁶⁰ ⁵⁵⁶⁵ ⁵⁵⁷⁰ ⁵⁵⁷⁵ ⁵⁵⁸⁰ ⁵⁵⁸⁵ ⁵⁵⁹⁰ ⁵⁵⁹⁵ ⁵⁶⁰⁰ ⁵⁶⁰⁵ ⁵⁶¹⁰ ⁵⁶¹⁵ ⁵⁶²⁰ ⁵⁶²⁵ ⁵⁶³⁰ ⁵⁶³⁵ ⁵⁶⁴⁰ ⁵⁶⁴⁵ ⁵⁶⁵⁰ ⁵⁶⁵⁵ ⁵⁶⁶⁰ ⁵⁶⁶⁵ ⁵⁶⁷⁰ ⁵⁶⁷⁵ ⁵⁶⁸⁰ ⁵⁶⁸⁵ ⁵⁶⁹⁰ ⁵⁶⁹⁵ ⁵⁷⁰⁰ ⁵⁷⁰⁵ ⁵⁷¹⁰ ⁵⁷¹⁵ ⁵⁷²⁰ ⁵⁷²⁵ ⁵⁷³⁰ ⁵⁷³⁵ ⁵⁷⁴⁰ ⁵⁷⁴⁵ ⁵⁷⁵⁰ ⁵⁷⁵⁵ ⁵⁷⁶⁰ ⁵⁷⁶⁵ ⁵⁷⁷⁰ ⁵⁷⁷⁵ ⁵⁷⁸⁰ ⁵⁷⁸⁵ ⁵⁷⁹⁰

the illustration heretofore given, the position of the "2" in 25 for the tens denomination is shown opposite the "7" regular keys, and the position of the "5", using the 5 right row of figures, is opposite the regular "5" key. In finding complement numbers no reference is to be had to the numbers the keys themselves bear, merely locate the row by means of the numbers given on the plate 10 3, as described.

Having thus described my invention, what I claim as new and desire to secure by Letters Patent is:—

1. In an adding machine of the class described having carrying mechanisms, dial reciprocating actuating members, a latch means for said reciprocating members, keys with suitable stems and means for releasing said latch means operated by the 15 depression of the key stems of said adding machine, the combination of an upright bar having thereon a cam surface, arranged approximately in line with the dials of said adding machine and adapted to coöperate 20 with said latch release means, coöperating therewith; a spring for returning said bar to normal position; a notch in said bar adapted to engage the top plate of the adding machine and retain said bar in depressed 25 position; a pin projecting from a reciprocating member in front of said bar into the path of travel of said bar, during the depression of the latter, and so positioned on said reciprocating members as to arrest the 30 movement of the latter at a point equal to that required to move the dials one numeral space; and a pin also projecting from said reciprocating members so arranged that during the depression of said bar it will 35 prevent any movement of said reciprocating member rearwardly, when a dial coöperating with the reciprocating member of lower denomination passes the transfer point thereon, substantially as described.

2. In an adding machine of the class described having carrying mechanisms, dial reciprocating actuating members, a latch means for said reciprocating members and means for releasing said latch means operated by the depression of the finger keys of 45 said adding machine, the combination of an upright bar having thereon a cam surface, arranged approximately in line with a dial of said adding machine and adapted to actuate said latch releasing means coöperating therewith; means for returning said bar to normal position; means for retaining said bar in depressed position; and two projections from the corresponding reciprocating 50 member, adapted to engage said bar when the latter is depressed, one of which projections being so positioned as to allow a movement in one direction sufficient to actuate its coöperating dial one numeral space, and the other projection being so positioned 55

as to prevent any transfer movement of said reciprocating members in the opposite direction, substantially as described.

3. In an adding machine of the class described, having carrying mechanisms, dial reciprocating actuating members, a latch means for restraining said reciprocating members, means for releasing said latch means connected to be operated by the depression of the key stems of said adding 70 machine, the combination of the upright bar 75 11 having the cam surface 11^a adapted to coöperate with the releasing means; a spring to return said bar to the normal position and a guide for said bar; a stop pin on one of said reciprocating actuating members back of said bar, adapted to abut said bar when the latter is depressed and allow a movement of said reciprocating members sufficient to actuate said dials one numeral 80 space; and a stop pin on said reciprocating members in front of said bar, so arranged as to prevent any movement of said reciprocating members rearwardly beyond normal, when a dial, coöperating with a reciprocating member of lower denomination, passes the transfer point, substantially as described.

4. In an adding machine of the class described having carrying mechanisms, dial reciprocating actuating members, a latch means for said reciprocating members and means for releasing said latch means operated by the depression of the finger keys of said adding machine, the combination of means for operating said releasing means 95 independently of the movement of the key stems of the adding machine, comprising suitable finger pieces arranged upon the top of said adding machine; connections from said finger pieces to said releasing means 100 and stops operated by said finger pieces adapted to limit the movement of said reciprocating members to one numeral space to actuate its coöperating dial one numeral space in one direction and prevent any transfer movement in the other direction, substantially as described.

5. In an adding machine of the class described, having dial reciprocating actuating members, a latch means for said reciprocating members and means for releasing said latch means operated by the depression of the regular finger keys of the keyboard, the combination of means for operating said releasing means independently of the movement of the key stems of the adding machine, comprising suitable finger pieces conveniently arranged, connections between said finger pieces and said releasing means; and stops operated by said finger pieces and adapted to limit the movement of said reciprocating members to one numeral space to actuate its coöperating dial one numeral space, substantially as described.

6. In an adding machine of the class de- 130

scribed having keys with suitable stems, dial reciprocating actuating members, a latch means for said reciprocating members and means for releasing said latch means 5 operated by the depression of the regular keys of the keyboard of said adding machine, the combination of means for operating said releasing means, independent of said regular keys; and interposing stops in 10 the path of travel of said reciprocating members to limit the movement of said reciprocating members during the operation of the reciprocating actuating members sufficient to actuate its coöperating dial one 15 numeral space in one direction and check said reciprocating members against any transfer movement in the opposite direction, substantially as described.

7. In an adding machine of the class described having keys with suitable stems, dial reciprocating actuating members, a latch means for said reciprocating members and means for releasing said latch means operated by the depression of the regular keys of the 20 keyboard of said adding machine, the combination of a depressible finger piece and means connected thereto for operating said releasing means independently of said regular keys of said keyboard; and interposing 25 stops in the path of travel of said reciprocating members to limit the movement of said reciprocating members during the operation of the reciprocating actuating members sufficient to actuate its coöperating dial 30 one space, substantially as described.

8. In an adding machine of the class described having dial reciprocating members, a stopping member, means for interposing said stopping member in the path of travel 40 of any of said reciprocating members and adapted to prevent movement in said reciprocating members, when the dial coöperating with the reciprocating member of the next lower denomination passes the transfer 45 point thereon, substantially as described.

9. In an adding machine of the class described, having a series of dials arranged for actuating the same; transfer means between the said dials; a stop means for stopping said transfer means at a desired point; and a key means at the left of said stop 50 means, positioned to limit the movement of the next dial to a single space, whenever an operative evolution of the machine in 55 the process of calculation is complete, coacting as specified.

10. In an adding machine having a series of dials, reciprocating actuating members therefor, a latch means for normally retaining 60 said reciprocating members from actuating said dials; key stems for limiting the actuating movement of said reciprocating members; connections between said key stems and said latch means; and means for 65 preventing the normal return of said key

stems bearing the numeral "1" thereon during the operating of said adding machine, comprising a locking member pivotally mounted in coöperative relation to said key stems, two engaging portions upon said locking member, and notches in said key stems adapted to receive the engaging portions of said locking member, when said key stems are in depressed position, substantially as described. 70 75

11. In an adding machine having a series of dials, reciprocating actuating members therefor, a latch means for normally retaining said reciprocating members from actuating said dials, key stems for limiting the actuating movement of said reciprocating members; connections between said key stems and said latch means; means for preventing the normal return of one of said key stems bearing the numeral "1" thereon 80 during the operation of said adding machine, comprising a locking member pivotally mounted in coöperative relation to said key stem; a locking portion upon said locking member; and means upon said key stem adapted to engage said locking portions of said locking member when said key stem is in depressed position, substantially as described. 85 90

12. In an adding machine having a series of dials, reciprocating actuating members therefor, a latch means for normally retaining said reciprocating members for actuating said dials; key stems for limiting the actuating movement of said reciprocating members and connections between said key stems and said latch means; means for preventing the normal return of said key stems bearing the numeral "1" thereon during the operation of said adding machine in the process of calculation, comprising a movable locking member; a locking portion upon said locking member; and means upon said key stems adapted to engage said locking portion when said key stems are in depressed position, substantially as described. 95 100 105

13. In an adding machine of the class described having numeral finger keys, and automatic key releasing means operative during the operation of the reciprocating actuating members of said adding machine, means for preventing the normal return of any depressed numeral finger key during the normal operating of said key releasing means upon any other depressed numeral keys of said adding machine, substantially as described. 115 120

14. In an adding machine of the class described having numeral finger keys, and an automatic key releasing means operative 125 during the operation of the reciprocating actuating members of said adding machine, means for rendering said automatic key releasing means inoperative upon any depressed finger key independently of the 130

other depressed numeral finger keys, substantially as described.

15. In an adding machine of the class described having a keyboard of numeral finger keys arranged in rows of numerical order from "1" to "9," a plate bearing thereon numerals from "8" to "0," successively, and so arranged in proximity to said keyboard that said numerals aline with the 10 numerical rows of said finger keys, the "8" on said plate being opposite the "1" key of the keyboard, and the "0" of said plate being opposite the "9" of said keyboard; and a secondary row of numerals on said 15 plate from "9" to "1," successively, adapted to aline with said numerical rows of said finger keys, the "9" of said secondary row being opposite the "1" finger key, and the "1" of said secondary row being opposite the "9" of said keyboard, for the purpose 20 specified and substantially as described.

16. In a machine of the class described having a keyboard of numerical finger keys arranged in rows of numerical order from 25 "1" to "9," a plate bearing thereon numerals from "8" to "0," successively, and so arranged in proximity to said keyboard that said numerals aline with the numerical rows of said finger keys, the "8" on said 30 plate being opposite the "1" of said keyboard, and the "0" of said plate being op-

posite the "9" key of the keyboard, for the purpose specified and substantially as described.

17. In an adding machine of the class 35 described having a keyboard of numerical finger keys arranged in numerical order from "1" to "9," each bearing a single numeral thereon, means external of said finger keys and in proximity thereto bearing a single set of numerals for indicating the remainder in the subtraction of the numeral of each of said finger keys from "9," for the purpose specified.

18. In an adding machine of the class 45 described, the combination of dials, reciprocating actuating members therefor, each of which is adapted to move one space beyond normal during the transfer operation of its coöperating dial, and means connected 50 to the keyboard of the machine for suppressing said additional one space movement of said reciprocating members, substantially as described.

In witness whereof I have hereunto set 55 my hand and seal in the presence of two witnesses.

GLENN J. BARRETT. [L. s.]
